W. BREWSTER

AUTOMOBILE DOOR

Filed July 14, 1925

FIG. 1.

FIG. 2.

FIG. 3.

FIG. 4.

Inventor
William Brewster
by

Attorney

UNITED STATES PATENT OFFICE.

WILLIAM BREWSTER, OF NEW YORK, N. Y.

AUTOMOBILE DOOR.

Application filed July 14, 1925. Serial No. 43,439.

To all whom it may concern:

Be it known that I, WILLIAM BREWSTER, a citizen of the United States, residing at the city of New York, county of New York, 5 and State of New York, have invented certain new and useful Improvements in Automobile Doors; and I do declare the following to be a full, clear, and exact description of the invention, such as will enable others skilled in the art to which it appertains to 10 make and use the same.

This invention relates to certain improvements in automobile front door construction, and has for its object to enable the 15 entire glass pane, usually contained in the top of the door, to be lowered and raised without any interference with the door lock construction or with the screws ordinarily used to secure the leaves of the hinges, or 20 without increasing the dimensions of the front door pillars, and is an improvement on the structure shown and described in Letters Patent No. 1,520,389, issued to me December 23, 1924.

With these ends in view the invention consists in certain details of construction and combination of parts such as will be hereinafter fully described and then specifically pointed out in the claim.

In the accompanying drawing which forms a part of this application

Figure 1 is a broken elevation of the front portion of an automobile body constructed in accordance with my improvement.

Figure 2 is a similar view showing my invention as applied when the doors are hinged at the front.

Figure 3 is a section at the line 3—3 of Figure 1, and

Figure 4 is a section at the line 4—4 of Figure 2.

Similar numerals of reference denote like parts in the several figures of the drawing. 1 is the automobile body and 2 the front 45 door, within the upper portion of which latter is the usual glass pane 3.

Referring to Figure 1 the cowl pillar 4 is undercut at 5 throughout the length of its bottom portion so as to provide a tongue-like member 6 as shown at Figure 3, and a recessed portion 6¹, while the outer edge of the door has an extended portion 7 which is tongue-like in shape and which, when the door is closed, fits closely within the cut away portion 6¹ of the cowl pillar, the

tongues 6, 7, thus forming a scarf or lap joint.

The lock mechanism is wholly located within the tongue portion 7 of the door and is indicated by dotted lines and is denoted by the numeral 8 while the striker plate of the lock mechanism is at the outer edge of the cut out portion of the cowl pillar and is shown in dotted lines and is indicated by the numeral 9.

It will thus be seen that all the lock mechanism of the door is located entirely within the extended tongue-like portion 7, and that the well 10 in the lower part of the door is entirely clear of the lock mechanism so that the glass pane 3 may be lowered within this well and raised without the slightest interference with such mechanism.

Referring to Figures 2 and 4, a construction is shown in which the door is hinged at the front edge, and in this instance the leaves 13 and 14 of the hinges 11 are secured respectively to the cowl pillar and the front edge of the member 7 of the door occupying the same positions with respect to the scarf joint members 6, 7, as the striker 9 and lock mechanism 8, above referred to, and the screws 14 that secure the leaves 13 to the door are wholly contained within the member 7 so as not to interfere with the operation of the window pane 3, these leaves and screws being shown in dotted lines at Figure 4.

When the lock mechanism of the door is at the rear edge thereof, as shown at Figure 2, the upper and lower body portions of the automobile may be as wide as desirable, and therefore provision need not be made for the operation of the glass pane in the door in the manner above specified.

From the foregoing description it will be clear that I have maintained the narrow windshield pillar post construction set forth in my Letters Patent aforesaid, but have eliminated the disadvantages incident to the fixed window panes adjacent said posts, since said panes necessitated rear frame portions, which latter in addition to the panes themselves were a menace to the clear vision of the driver.

With the entire front door panes lowered and the narrow pillar posts of the windshield utilized, the view of the driver is unobstructed in the slightest degree.

What is claimed is:—

In an automobile front door construction in which the upper portion is provided with a drop glass pane, while the lower portion contains a pocket within which said pane may be dropped, the combination of a scarf-joint member extending from one edge of the lower half of the door, with a similar scarf-joint member formed in the adjacent edge of that part of the automobile body

which forms one side of the door casing, the fixtures of the door, as the lock or hinges, being wholly contained within said scarf-joint members, whereby the movements of said pane within said pocket are unimpeded.

In testimony whereof I affix my signature hereto.

WILLIAM BREWSTER.
